(57) **CLAIM**

The ornamental design for a image for a digital camera, as shown and described.

DESCRIPTION

FIG. 1 is a perspective view of an image for a digital camera; and,

FIG. 2 is a front view thereof.

The broken line drawings of the element within the image of the digital camera, and the digital camera are for illustrative purposes only and form no part of the claimed design.

1 Claim, 2 Drawing Sheets

FIG. 1

FIG. 2
